UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

SHOE-LEVELING MACHINE.

Application filed April 18, 1928. Serial No. 271,051.

This invention relates to machines for use in the manufacture of boots and shoes for performing what is commonly termed the leveling operation, and more particularly to machines of that type in which a shoe support and a leveling tool, such as a roll, are relatively movable lengthwise of a shoe on the support to cause the tool to operate progressively along the bottom of the shoe. 5 While such machines are used principally for shaping the outsoles of shoes, they are also sometimes used to prepare the bottom of a lasted shoe for the reception of the outsole, and the term "leveling" is accordingly 10 employed herein in a general sense to comprehend such different uses. The invention is herein illustrated in its application to a machine organization of the same general type as that disclosed in Letters Patent 15 No. 1,667,761, granted on May 1, 1928 upon an application of E. E. Winkley and H. A. Davenport, and in various Letters Patent 20 therein referred to, although it is to be understood that the invention is not thus limited in its applicability. 25

Leveling machines of the above-mentioned type have been commonly so designed as to confine the action of the leveling roll substantially to the forepart and shank portions 30 of the shoe bottom. Shoes, however, frequently require more or less shaping of the heel end portion of the sole, and it has been the general practice to perform this operation manually, when needed, by the 35 use of a hammer, although it has been proposed to level the heel end of the shoe in the leveling machine by the use of a supplemental roll, as disclosed in a copending application of H. A. Davenport, Serial 40 No. 147,007, filed on November 8, 1926. In order to level satisfactorily all portions of the heel end of the sole by a leveling roll, it is necessary that the roll in its operation pass to the rear of the heel end of the shoe; 45 and this involves the necessity of controlling the roll in such manner as to prevent it from distorting the edge of the sole in leaving the shoe or in returning to a position over the shoe.

50 The present invention, in one important aspect, accordingly provides an improvement in means for controlling a leveling tool or roll in leaving an end of a shoe or in returning to a position over the shoe. The in-

vention is illustrated as applied to an organization including a supplemental roll for operating upon the heel end of the shoe in accordance with the general disclosure of the above-mentioned Davenport application, although it is not limited to an organization 55 of that particular character. For the purposes in view, the construction shown comprises a roll support or receiver which is movable heightwise of the shoe to a position determined by engagement of the supplemental roll with the heel end of the shoe and is automatically locked against any substantial movement in the direction of the pressure applied by the roll from the position thus determined, the locking of the roll 60 support being controlled by the relative movement of the shoe support and the rolls lengthwise of the shoe. Accordingly, as the roll which operates on the heel end of the shoe passes to the rear of the heel end, 65 which results in the construction shown from swinging movement of the shoe support or jack relatively to the roll, it is supported and held automatically against movement below the plane of the heel seat, so that 70 neither in leaving the shoe nor in its return to a position over the bottom of the shoe is there any danger of damage to the edge 75 of the sole. As herein illustrated, the roll support is carried by the jack and is so 80 mounted and controlled that after it arrives in roll-supporting position it is stopped and held in that position while the jack continues its movement to carry the shoe past 85 the roll. It is a further characteristic of 90 the construction shown that the means for locking the roll support as above described acts also automatically to unlock it immediately upon the return of the roll to a position over the heel end of the shoe in the reverse 95 movement of the jack, to permit the leveling pressure to be again applied.

In operating upon some kinds of shoes it is desirable to prevent a leveling tool or roll that operates upon the heel end of the shoe 100 from operating upon some other portion of the shoe, in order to avoid danger of possible damage to the shoe or danger of distorting by the action of the heel end roll the shape produced by another roll. In operating, for example, upon shoes having high-arched shanks, it is desirable to prevent the heel end roll from engaging the ball portion 105

of the shoe which, in the leveling machine, is positioned at a height considerably above the heel-seat. In view of this and other considerations, the invention further provides 5 novel means for controlling, with respect to movement heightwise of the shoe, a leveling tool or roll which operates on the heel end of the shoe, or, in another aspect, for controlling different leveling tools or rolls 10 with respect to such movement. As herein illustrated, there is provided automatic means for controlling the different rolls independently of each other, so that the roll which operates at the heel end is moved into 15 and out of engagement with the shoe at different times from the other roll to avoid contact with portions of the shoe upon which it is not desired that it shall operate.

The above and other features of the invention, including also novel means for manually controlling the tool support with respect to movement toward or from the shoe, and various novel details of construction and combinations of parts, will now be more 20 particularly described by reference to the accompanying drawings and pointed out in the claims.

In the drawings,

Fig. 1 is a view in side elevation of a machine in which the invention is embodied;

Fig. 2 is a perspective view of a portion of the machine; and

Fig. 3 is a view substantially in side elevation on a larger scale of portions of the structure shown in Fig. 1, with the parts as they appear at an intermediate stage in the 35 cycle of the machine.

Leveling machines of the type illustrated are twin machines including two sets of operating instrumentalities for operating respectively on different shoes in different locations in the machine. For the purpose of an understanding of this invention only one of these sets of instrumentalities is shown 40 in the drawings and will be hereinafter described, since it will be understood that mechanism such as illustrated will be substantially duplicated in the opposite half of the machine, and it is further to be understood 45 that the invention is not limited to machines of the twin type.

For supporting a shoe *a* to receive the leveling pressure the machine is provided with a shoe support or jack comprising a 50 heel post 10 and a toe post 12 which are relatively adjustable about an axis at 14 by means of a hand wheel 16 for shoes of different sizes, the jack as a whole being movable about an axis at 18 to carry the shoe 55 forwardly and rearwardly under a leveling tool or roll 20 for applying leveling pressure to the forepart and shank portions of the shoe bottom. The leveling roll 20 is mounted on a holder 22 which is supported on a 60 roll carrier 24 pivoted at 26 on the frame of

the machine for swinging movements in a vertical plane to press the roll upon the shoe and to withdraw it from the shoe at different times in the cycle of operations. To cause the roll to operate progressively 70 along the bottom of the shoe the jack is swung about its axis 18 by power-operated mechanism, which it is unnecessary to describe in detail since it is fully described in prior Letters Patent including those hereinbefore referred to. The cycle of operations, which may be variously modified as far as the present invention is concerned, may comprise as heretofore first a full forward movement of the jack to cause the roll 75 so 20 to traverse the shoe bottom from the toe end to the rear end of the shank, then a plurality of short backward and forward movements while the roll is operating at one side of the shank, thereafter long backward 80 and forward movements to cause the roll to return to the toe end along one side and then to operate from the toe to the rear of the shank along the opposite side, followed by a plurality of short backward and forward 85 movements while the roll is operating at that side of the shank and finally a movement to cause the roll to return to the toe. In the course of these operations the roll 90 may be tipped in various ways by movement of its holder 22, as also fully disclosed in the prior Letters Patent.

At the beginning of the operation of the machine the roll 20 is supported in a position somewhat above the level of the toe end 100 of the shoe, as illustrated in Fig. 1, by yieldable means including a spring plunger 27, as fully disclosed in the Winkley and Davenport patent hereinbefore mentioned. For moving the roll down into engagement 105 with the toe end of the shoe bottom at the beginning of the cycle of operations and for releasing it to permit it to be raised by the plunger 27 at the end of the cycle, there is provided a cam wheel 28 on a cam shaft 30, the periphery of this cam wheel being arranged to act on a lever 32 connected by a link 34 to a lever 36 on the frame of the machine. The lever 36 is arranged to bear upon the upper end of a plunger 38 which 110 acts through a spring 40 on a lever 42 connected by a link 44 to the roll carrier 24. Through these connections the roll 20 is made to bear yieldingly upon the bottom of the shoe. As illustrated, the cam wheel 28 115 is so formed as to adapt it to relieve the pressure of the roll 20 on the shoe at certain times between the beginning and the end of the cycle; but there is preferably also provided means for rendering it ineffective thus 120 to relieve the pressure in operating on shoes that do not require such pressure relief, as disclosed in Letters Patent No. 1,685,387, granted on September 25, 1928 upon an application of E. E. Winkley and F. V. Hart. 125 130

The machine herein shown is further provided with an additional levelling tool or roll 46 for applying leveling pressure to the heel end of the shoe bottom while the roll 20 is operating upon other portions, especially the shank. This roll is mounted for turning movement in a holder 48 having an upwardly extending shank 50 mounted in a roll carrier bracket 52 which is secured to another bracket 54 pivoted at 56 on a roll carrier arm or lever 58 pivotally mounted at 60 on the frame of the machine. The holder 48 can be turned about the axis of its shank 50 to position the roll 46 at different angles laterally of the shoe, and it is secured in adjusted position by means of a screw 62 whereby the shank 50 is clamped in the bracket 52. The bracket 52 is secured to the bracket 54 by clamping screws 64 which extend through slots in the bracket 52, as shown in Fig. 2, to permit the roll to be adjustably tipped about an axis extending lengthwise of the shoe. By movement of the bracket 54 about the axis of its pivot 56 the roll 46 may be positioned at different distances lengthwise of the shoe from the roll 20, and the bracket 54 is secured in adjusted position by means of a clamping screw 66 on the arm 58. The means thus far described for supporting and adjusting the roll 46 is similar to what is disclosed in the Davenport application hereinbefore mentioned.

the heel seat. For this purpose the cam shaft 30 carries a path cam 68 which engages a roll on one end of a lever 70 pivoted at 72 on the frame of the machine, the other end of this lever being connected to a rod 74 which is slidably movable through a bushing 76 threaded in one end of a sleeve member 78 which is pivotally mounted at 80 on the arm 58. Between the bushing 76 and a flange 82 on the rod 74 there is mounted a spring 84 through which pressure is applied yieldingly to the arm 58 by the lever 70 to force the roll 46 downwardly against the shoe. The rod 74 carries at its outer end nuts 86 for engaging the bushing 76 to afford a positive connection between the lever 70 and the arm 58 to lift the roll 46 from the shoe. The path cam 68 is so formed as to force the roll 46 downwardly upon the shoe when the jack has been moved far enough forwardly to bring the shoe substantially into position for this roll to act on its heel end portion, and to lift the roll from the shoe at the corresponding time in the reverse movement of the jack, the roll thus being lowered and lifted in each full reciprocation of the jack in the cycle of the machine.

In order that the roll 46 shall apply its pressure evenly to all portions of the heel end of the shoe bottom, it is desirable that in each forward movement of the jack the heel end of the shoe shall be carried beyond

35 mentioned.

For one of the purposes of the present invention the machine is provided with novel means for controlling the roll 46 with respect to movement heightwise of the shoe into or out of engagement with the shoe. It is desirable that this roll be positioned close enough to the roll 20 so that it may operate upon the heel end of the shoe while the roll 20 is operating on the shank portion of the shoe. With the two rolls in that relation to each other there are times in the cycle of the machine when the roll 46 is located over the forepart of the shoe, as illustrated for example in Fig. 1. It is usually preferable, however, that the roll 46 be confined in its operation substantially to the heel end of the shoe, in order to avoid objectionable results such as might arise from its engagement with other portions of the shoe. Automatic means is accordingly provided for controlling the roll-carrying arm 58 independently of the carrier 24 for the roll 20, so that in the forward movement of the jack the roll 46 is not moved downwardly into engagement with the shoe until that time in the cycle when it is positioned substantially or approximately over the heel end of the shoe, and so that in the reverse movement of the jack it is lifted out of engagement with the shoe before the parts are in position for it to act to any substantial extent on portions of the shoe bottom in front of this roll. In order, however, to avoid danger of damage to the rear edge of the sole, it is necessary to prevent the roll in that movement of the jack from dropping off the heel end of the shoe and also to control it in such manner as to prevent it from delivering a blow on the rear edge of the sole in its return to a position over the shoe bottom in the reverse movement of the jack. The invention accordingly further provides novel means for accomplishing this result. For the purpose in view there is pivotally mounted at 88 on the heel-supporting portion 10 of the jack an arm 90 which carries a roll-supporting device on its upper end. The arm 90 is provided with a lug 92 engaged by a spring plunger 94 tending to swing the arm forwardly toward the heel end of the shoe and for limiting the swinging movement in this direction the arm carries a rubber pad 96 arranged to engage the heel end face of the shoe. Slidably mounted in a bore in the arm 90 is a rod or plunger 98 fast on the upper end of which is a bracket 100 having mounted thereon a U-shaped roll supporting member or roll receiver 102. The two arms of this member are arranged to extend forwardly at opposite sides of the heel end of the shoe and are provided with inclined faces 104 arranged to be engaged by diametrically reduced portions 106 at the opposite ends

of the roll 46, and also with hollows or depressions 108, one of which is shown in Figs. 1 and 2, arranged to receive these reduced portions of the roll. A spring 110 in the 5 arm 90 acts on the plunger 98 to hold the member 102 initially at such a height that the reduced portions 106 of the roll engage the inclined faces 104 and force this member and its supporting bracket 100 downwardly against the resistance of the spring 10 as the jack is moved forwardly to cause the roll to operate along the heel seat, the reduced portions of the roll entering the depressions 108 before the shoe is moved far 15 enough to carry it beyond the roll. The member 102 is provided with a spindle 112 mounted in the bracket 100 for turning movement about an axis extending lengthwise of the shoe, so that the member 102 20 can tip laterally to adjust itself to the direction of the axis of the roll 46. For limiting such tipping movement the spindle 112 is provided with a projection 114 which extends into a slot formed in the bracket 100, 25 as shown in Fig. 2. To prevent turning movement of the roll support about the axis of the plunger 98 the bracket 100 has a pair of downwardly extending arms 116, only one of which is seen in the drawings, these arms 30 being arranged to engage lugs 118 projecting laterally from the upper end of the arm 90. To limit adjustably upward movement of the roll support in response to the action of the spring 110, one of the arms 116 carries a screw 120 for engaging the lug 118 35 at that side of the arm 90.

It will thus be seen that as the roll 46 operates on the heel end portion of the shoe bottom the roll support, comprising the 40 members 100 and 102, is adjusted automatically by the action of the roll to a height determined by engagement of the roll with the heel end of the shoe bottom. To render the roll support effective to prevent any 45 substantial downward movement of the roll below the plane of the heel seat when the roll is positioned at the rear of the heel end of the shoe, there is further provided means for locking the support against any substantial downward movement from the position to which it is adjusted in the manner 50 above described. For this purpose the arm 90 is provided with a series of upwardly directed ratchet teeth 122 and the downwardly extending arms 116 of the bracket 100 carry a pair of pawls or latches 124 pivotally mounted on a rod 126 which extends across from one arm to the other. The ends of these pawls are spaced apart 55 vertically a distance less than the distance between adjacent ratchet teeth for the purpose of greater precision. Each pawl is provided with a tail portion 128, and associated therewith is a pawl controller comprising a curved arm 130 also pivoted on 60

the rod 126 and having on its lower end laterally extending lugs which carry rods 132 (Fig. 3) projecting upwardly through openings in the tails 128 of the pawls, these rods having thereon springs 134 through 70 which the pawls are swung inwardly against the ratchet teeth in response to swinging movement of the arm 130 toward the left (Fig. 3). Such movement of the arm 130 is effected automatically at a time in the 75 cycle before the roll reaches the rear edge of the heel end of the shoe bottom by the action of a portion of the roll-carrying bracket member 52 upon a screw 136 adjustably mounted in a holder 138 secured to the 80 upper end of the arm 130. Prior to that time in the cycle the pawls 124 are held out of engagement with the ratchet teeth by the action of the arm 130 upon their tail portions 128 under the influence of a spring 85 139 the opposite ends of which are connected respectively to the arm 130 and to the member 100. A shoulder 140 on the arm 130 is arranged to engage the member 100 to limit its movement under the force of the spring 90 139, as shown in Figs. 1 and 2.

It is desirable that before a shoe is mounted on the jack the means for supporting the roll at the heel end shall be swung away from the shoe-supporting portion of 95 the jack, that is, to the left from the position that it occupies in Fig. 1, so as not to interfere with the presentation of the shoe. For this purpose there is conveniently utilized mechanism such as provided heretofore for use in jacking the shoe, features of 100 which are described and claimed in a co-pending application of E. E. Winkley and H. A. Davenport, Serial No. 12,287, filed on February 28, 1925. This mechanism 105 comprises a pivoted hand lever 142 having arms that extend at opposite sides of the heel post 10, as shown in Fig. 2, and connected by means fully described in the above-mentioned application to a bar 144 110 which acts on a swinging heel-pin carrier 146 to tip the shoe in a direction to force its toe end down upon a toe rest 148. It will be understood that such jacking of the shoe is effected by downward movement of 115 the hand lever, and that prior to the jacking operation the lever occupies a position higher than that in which it is shown in the drawings. In order to utilize this lever to control the roll support, the arm 90 is 120 provided with a projection 150 having portions at the opposite sides of the arm on which are formed inclined lower faces 152, and the two side arms of the lever 142 are provided with rolls 154 in position to engage these inclined faces and thereby to 125 force the arm 90 rearwardly against the resistance of the spring plunger 94. When the shoe is jacked by downward movement of the lever, the arm 90 is released and is 130

swung toward the shoe by the plunger 94 until the pad 96 engages the end face of the shoe.

In the operation of the machine, a shoe is first mounted on the jack and the lever 142 is then moved downwardly by the operator to jack the shoe firmly on the toe rest 148 and to release the arm 90 and permit it to be swung toward the heel end of the shoe in the manner above described. The jack is then swung forward manually to the position indicated in Fig. 1, as usual in machines of the type illustrated. Upon the starting of the machine the jack is swung forwardly by its cam and the forepart and shank-leveling roll 20 is moved downwardly to engage the shoe in the well-known manner characteristic of machines of this type. Downward movement of the heel end leveling roll 46, however, is delayed until the heel end portion of the shoe arrives substantially in position to receive the pressure of the roll. The roll 46 is then forced downwardly by the action of its cam 68, and is held in its lowered position under the influence of the spring 84 until such time as in the reverse swinging movement of the jack the roll 20 is caused to return to the toe end of the shoe, whereupon the roll 46 is lifted by its cam to prevent it from engaging the shoe for any substantial distance forwardly of the heel seat. It will be understood that in a cycle of operations such as hereinbefore described the roll 46 is thus lifted twice in the cycle in time relation to the return of the roll 20 to the toe and is depressed twice in time relation to the progress of the roll 20 from the toe end rearwardly. If the cycle includes, as hereinbefore described, a plurality of short reciprocations of the jack to cause the roll 20 to operate repeatedly along each side of the shank, the roll 46 simultaneously operates repeatedly along the heel seat. Each time that the roll 46 operates rearwardly along the heel seat, its reduced end portions 106 engage the inclined faces 104 of the roll-supporting member 102 and depress this member and its supporting bracket 100 to a position determined by engagement of the roll with the heel seat face of the shoe, the reduced portions of the roll entering the depressions 108 just before the shoe is in position to pass from under the roll. Each time that the shoe is moved forwardly far enough to carry its heel end beyond the roll 46, the pawls 124 are moved into engagement with the ratchet teeth 122 by the action of the roll-carrying bracket 52 on the arm 130, so that the roll support is locked against any substantial downward movement from the position determined by the roll in engagement with the heel seat. The roll is thus supported at such a height as to prevent it from dropping downwardly at

the rear end of the shoe in such manner as to bend the edge of the sole and in position for the shoe to be moved under it again without damage to the sole. It will be understood that after the engagement of the pawls 124 with the ratchet teeth, which occurs just as the reduced portions of the roll enter the depressions 108 in the member 102, the roll support and the arm 90 on which it is mounted are held from further forward movement with the jack by contact of the roll with the member 102 in the depressions 108, assisted by the contact of the bracket 52 with the screw 136 on the arm 130. There thus occurs a relative separating movement of the shoe and the roll-supporting parts against the resistance of the spring plunger 94 while the shoe is moved forward to cause the roll 20 to operate along the rear end portion of the shank. In the reverse swinging movement of the jack the shoe is returned toward the roll support until its rear end face engages the pad 96, and then the roll support is carried rearwardly with the shoe simultaneously with the withdrawal of the pawls 124 from engagement with the ratchet teeth, so that the roll 46 is again permitted to apply its pressure to the heel end portion of the sole.

The invention is herein illustrated with reference to the application of leveling pressure to a shoe of the stitchdown type, but it is to be understood that it is not limited to use in operating on shoes of that particular type but is generally applicable to machines for leveling various kinds of shoes.

Having described the invention, what I claim as new and desire to secure by Letters Patent of the United States is:

1. In a leveling machine, a shoe support and a leveling tool relatively movable lengthwise of a shoe on said support to cause the tool to operate progressively along the bottom of the shoe, and means arranged to act at a predetermined point in such relative movement to support the tool independently of the shoe against movement in the direction of the leveling pressure, said means comprising a tool-supporting device automatically adjustable heightwise of the shoe to a position determined by the shoe and including also mechanism for automatically securing said device against any substantial movement from adjusted position in the direction of said pressure.

2. In a leveling machine, a shoe support and a leveling tool relatively movable lengthwise of a shoe on said support to cause the tool to operate progressively along the bottom of the shoe and to pass beyond an end of the shoe and also relatively movable heightwise of the shoe to apply the leveling pressure, and means for preventing such relative heightwise movement of the

- tool and support when the tool is beyond the end of the shoe, said means comprising a device automatically adjustable heightwise of the shoe to a position determined by the 5 shoe and including also mechanism for automatically securing said device against any substantial movement from adjusted position in the direction of the relative pressure-applying movement of the tool and support.
- 10 3. In a leveling machine, a shoe support and a leveling tool relatively movable lengthwise of a shoe on said support to cause the tool to operate progressively along the bottom of the shoe and to pass beyond an end of the shoe, and means arranged to support the tool against movement in the direction of the leveling pressure when the tool is beyond the end of the shoe, said means comprising a tool-supporting device.
- 15 20 25 4. In a leveling machine, a shoe support and a leveling tool relatively movable lengthwise of a shoe on said support to cause the tool to operate progressively along the bottom of the shoe and to pass beyond an end of the shoe, and means arranged to support the tool against movement in the direction of the leveling pressure when the tool is beyond the end of the shoe, said means comprising a tool-supporting device automatically adjustable heightwise of the shoe to a position determined by engagement of the tool with the bottom of the shoe and including also mechanism for automatically locking said device against any substantial movement from adjusted position in the direction of the leveling pressure.
- 30 35 40 45 50 55 60 65 70 75 80 85 90 95 100 105 110 115 120 125 130
5. In a leveling machine, a shoe support and a leveling tool relatively movable lengthwise of a shoe on said support to cause the tool in its operation to pass beyond an end of the shoe and thereafter to return to a position over the end of the shoe, and means arranged to support the tool at the end of the shoe until it is again positioned over the shoe, said means comprising a tool-supporting device automatically adjustable to a position determined by the engagement of the tool with the shoe and including also mechanism for automatically securing said device against any substantial movement in the direction of the leveling pressure from the position thus determined.
6. In a leveling machine, a shoe support and a leveling roll relatively movable lengthwise of a shoe on said support to cause the roll in its operation to pass beyond an end of the shoe and thereafter to return to a position over the end of the shoe, a roll receiver arranged to support the roll beyond the end of the shoe, said receiver being automatically adjustable heightwise of the shoe to a position determined by the engagement of the roll with the shoe, and automatic means for locking the roll receiver before the roll leaves the shoe against any substantial movement in the direction of the leveling pressure from the position thus determined and for unlocking it when the roll is again over the end of the shoe.
7. In a leveling machine, a shoe support and a leveling roll relatively movable lengthwise of a shoe on said support to cause the roll in its operation to pass beyond an end of the shoe and thereafter to return to a position over the end of the shoe, a roll receiver arranged to support the roll beyond the end of the shoe, said receiver being de- 70 75 80 85 90 95 100 105 110 115 120 125 130
- pressible by the roll to a position determined by the engagement of the roll with the shoe, and a pawl and ratchet device controlled by the relative movement of the shoe support and the roll lengthwise of the shoe for locking the roll receiver before the roll leaves the shoe against any substantial further depression from the position thus determined and for unlocking it when the roll is again over the end of the shoe.
8. In a leveling machine, a shoe support and a leveling tool relatively movable lengthwise of a shoe on said support to cause the tool to traverse the bottom of the heel end of the shoe and to pass to the rear of the heel end, and a device arranged to be moved automatically heightwise of the shoe to a position determined by engagement of the tool with the heel end of the shoe and to be secured independently of the shoe against any substantial further movement in the same direction for determining the position of the tool when at the rear of the heel end of the shoe.
9. In a leveling machine, a shoe support and a leveling tool relatively movable lengthwise of a shoe on said support to cause the tool to traverse the bottom of the heel end of the shoe and to pass to the rear of the heel end, a member controlled by the tool and arranged to assume a position heightwise of the shoe determined by engagement of the tool with the heel end of the shoe for supporting the tool when at the rear of the heel end, and automatic means for securing said member against any substantial movement in the direction of the leveling pressure beyond the position thus determined.
10. In a leveling machine, a shoe support and a leveling tool relatively movable lengthwise of a shoe on said support to cause the tool to traverse the bottom of the heel end of the shoe and to pass to the rear of the heel end, a member controlled by the tool

and arranged to assume a position heightwise of the shoe determined by engagement of the tool with the heel end of the shoe for supporting the tool when at the rear of the heel end, and a latch controlled by the relative movement of the shoe support and the tool for securing said member against any substantial movement in the direction of the leveling pressure beyond the position thus determined.

11. In a leveling machine, a shoe support and a leveling tool relatively movable lengthwise of a shoe on said support to cause the tool to traverse the bottom of the heel end of the shoe and to pass to the rear of the heel end, and means for supporting the tool independently of the shoe at the rear of the heel end of the shoe, said means comprising a tool-supporting device adjustable heightwise of the shoe to a predetermined position in response to the action of the tool thereon and including also mechanism controlled by the relative movement of the shoe support and the tool lengthwise of the shoe for securing said device against any substantial movement from said position in the direction of the leveling pressure.

12. In a leveling machine, a shoe support and a leveling tool relatively movable lengthwise of a shoe on said support to cause the tool to traverse the bottom of the heel end of the shoe and to pass to the rear of the heel end, a tool support movable automatically heightwise of the shoe to a position determined by the shoe for supporting the tool at the rear of the heel end, and pawl and ratchet mechanism controlled by the relative movement of the shoe support and the tool for locking said tool support against any substantial movement in the direction of the leveling pressure from the position thus determined.

13. In a leveling machine, a shoe support and a leveling roll relatively movable lengthwise of a shoe on said support to cause the roll to traverse the bottom of the heel end of the shoe and to pass to the rear of the heel end, a roll receiver at the heel end of the shoe for supporting the roll at the rear of the heel end, said receiver being movable automatically to a position determined by engagement of the roll with the heel end of the shoe, and automatic means for locking said receiver against any substantial movement in the direction of the leveling pressure from the position thus determined.

14. In a leveling machine, a shoe support and a leveling roll relatively movable lengthwise of a shoe on said support to cause the roll to traverse the bottom of the heel end of the shoe and to pass to the rear of the heel end, a roll receiver at the heel end of the shoe for supporting the roll at the rear of the heel end, means for yieldingly supporting said receiver for movement heightwise

of the shoe to a position determined by engagement of the roll with the bottom of the shoe, and an automatically controlled pawl and ratchet device for locking said receiver against any substantial movement in the direction of the leveling pressure from the position thus determined. 70

15. In a leveling machine, a leveling tool, a shoe support movable to cause the tool to traverse the bottom of the heel end of a shoe thereon and to pass to the rear of the heel end, a device movable with the shoe support for supporting the tool at the rear of the heel end of the shoe against movement in the direction of the leveling pressure, said device being movable heightwise of the shoe to a position determined by the shoe, and mechanism controlled by the movement of the shoe support for securing said device against any substantial movement in the direction of the leveling pressure from the position thus determined. 75

16. In a leveling machine, a leveling roll, a shoe support movable to cause the roll to traverse the bottom of the heel end of a shoe thereon and to pass to the rear of the heel end, a roll receiver movable with the shoe support for supporting the roll at the rear of the heel end of the shoe against movement in the direction of the leveling pressure, said roll receiver being arranged to be depressed under control of the roll to a height determined by the shoe as the roll traverses the heel end of the shoe, and automatic means for then locking said receiver against any substantial further depression to hold it in supporting position. 90

17. In a leveling machine, a leveling roll, a shoe support movable to cause the roll to traverse the bottom of the heel end of a shoe thereon and to pass to the rear of the heel end, a roll receiver movable with the shoe support for supporting the roll at the rear of the heel end of the shoe against movement in the direction of the leveling pressure, said roll receiver being arranged to be depressed by the action of the roll to a height determined by the shoe as the roll traverses the heel end of the shoe, and a pawl and ratchet device controlled by the movement of the shoe support for locking said receiver against any substantial further depression to hold it in supporting position. 105

18. In a leveling machine, a shoe support and a leveling roll relatively movable lengthwise of a shoe on said support to cause the roll to traverse the bottom of the heel end of the shoe and to pass to the rear of the heel end, and a roll receiver at the heel end of the shoe movable heightwise of the shoe to a position determined by engagement of the roll with the bottom of the shoe for supporting the roll at the rear of the heel end, said receiver being constructed to support the roll at the opposite sides of the heel end 110

of the shoe and being mounted for turning movement about an axis extending lengthwise of the shoe to adjust itself to the direction of the axis of the roll.

5 19. In a leveling machine, a shoe support and a leveling roll relatively movable lengthwise of a shoe on said support to cause the roll to traverse the bottom of the heel end of the shoe and to pass to the rear of the heel end, said roll having portions at its opposite ends reduced in diameter, and a roll receiver constructed to engage said reduced portions of the roll to support it against movement in the direction of the leveling pressure when it is positioned at the rear of the heel end of the shoe.

20. In a leveling machine, a shoe support and a leveling roll relatively movable lengthwise of a shoe on said support to cause the roll to traverse the bottom of the heel end of the shoe and to pass to the rear of the heel end, said roll having portions at its opposite ends reduced in diameter, and a roll receiver arranged to support the roll against movement in the direction of the leveling pressure when it is at the rear of the heel end of the shoe, said roll receiver having portions at the opposite side of the heel end of the shoe with depressions therein for receiving said reduced portions of the roll.

21. In a leveling machine, a shoe support and a leveling roll relatively movable lengthwise of a shoe on said support to cause the roll to traverse the bottom of the heel end of the shoe and to pass to the rear of the heel end, said roll having portions at its opposite ends reduced in diameter, and a roll receiver arranged to support the roll against movement in the direction of the leveling pressure when it is at the rear of the heel end of the shoe, said roll receiver being yieldingly supported for movement heightwise of the shoe to a position determined by engagement of the roll with the bottom of the shoe and having portions at the opposite sides of the heel end of the shoe arranged to be engaged by said reduced portions of the roll for imparting to the receiver its positioning movement.

22. In a leveling machine, a shoe support and a leveling tool relatively movable lengthwise of a shoe on said support to cause the tool to operate progressively along the bottom of the shoe and to pass beyond an end of the shoe, and a device for supporting the tool against movement in the direction of the leveling pressure when the tool is beyond the end of the shoe, said device and the shoe support being arranged to maintain a fixed relation to each other lengthwise of the shoe during a portion of the relative movement of the shoe support and the tool and then to have a relative separating movement lengthwise of the shoe

in the further relative movement of the support and tool.

23. In a leveling machine, a shoe support and a leveling tool relatively movable lengthwise of a shoe on said support to cause the tool to traverse the bottom of the heel end of the shoe and to pass to the rear of the heel end, and a device for supporting the tool against movement in the direction of the leveling pressure when the tool is at the rear of the heel end of the shoe, said device and the shoe support being arranged to maintain a fixed relation to each other lengthwise of the shoe in the relative movement of the shoe support and the tool until the device and the tool are in operative relation to each other and then to have a relative separating movement lengthwise of the shoe in response to the action of the tool on said device in the further relative movement of the shoe support and the tool.

24. In a leveling machine, a shoe support and a leveling tool relatively movable lengthwise of a shoe on said support to cause the tool to traverse the bottom of the heel end of the shoe and to pass to the rear of the heel end, and a device for supporting the tool against movement in the direction of the leveling pressure when the tool is at the rear of the heel end of the shoe, said device and the shoe support being relatively movable lengthwise of the shoe, and yieldable means for maintaining said device in fixed relation to the length of the shoe in the relative movement of the shoe support and the tool until the device and the tool are in operative relation to each other, the tool being arranged to act on said device in the further relative movement of the support and tool to effect a relative separating movement of said device and the shoe against the resistance of said yieldable means.

25. In a leveling machine, a leveling tool, a shoe support movable to cause the tool to operate progressively along the bottom of a shoe thereon and to pass beyond an end of the shoe, and a device movable with the shoe support into position to support the tool beyond the end of the shoe against movement in the direction of the leveling pressure, the machine being constructed to stop said device when it arrives in tool-supporting position and to hold it in that position while the shoe support continues its movement to carry the shoe past the tool.

26. In a leveling machine, a leveling tool, a shoe support movable to cause the tool to traverse the bottom of the heel end of a shoe thereon and to pass to the rear of the heel end, a device movable with the shoe support into position to support the tool at the rear of the heel end of the shoe against movement in the direction of the leveling pressure, said device and the shoe

support being relatively movable lengthwise of the shoe, and a spring for holding said device normally in a position relatively close to the heel end of the shoe, the machine being constructed to stop said device when it arrives in tool-supporting position and to hold it in that position against the resistance of said spring while the shoe support continues its movement to carry the shoe past the tool.

27. In a leveling machine, a leveling roll, a jack movable to cause the roll to traverse the bottom of the heel end of a shoe thereon and to pass to the rear of the heel end, a roll receiver carried by the jack for supporting the roll at the rear of the heel end of the shoe, said roll receiver and the jack being relatively movable lengthwise of the shoe and the receiver being depressible to a height determined by engagement of the roll with the heel end of the shoe, and a device for locking said receiver against further depression, the machine being constructed to actuate said locking device at a predetermined point in the movement of the jack and to stop the receiver and hold it in roll-supporting position while the jack continues its movement to carry the shoe past the roll.

28. In a leveling machine, a leveling roll, a roll carrier, a jack movable to cause the roll to traverse the bottom of the heel end of a shoe thereon and to pass to the rear of the heel end, a roll receiver carried by the jack for supporting the roll at the rear of the heel end of the shoe, said roll receiver and the jack being relatively movable lengthwise of the shoe and the receiver being depressible to a height determined by engagement of the roll with the heel end of the shoe, a pawl for locking said receiver against further depression, and a pawl controller arranged to be carried into engagement with the roll carrier to actuate said pawl, the machine being constructed to stop the roll receiver when the pawl is thus actuated and to hold it in roll-supporting position while the jack continues its movement to carry the shoe past the roll.

29. In a leveling machine, a leveling roll, a jack movable to cause the roll to traverse the bottom of the heel end of a shoe thereon and to pass to the rear of the heel end, an arm mounted on the jack for swinging movement lengthwise of the shoe, a roll receiver yieldingly supported on said arm for depressing movement to a predetermined height in response to action of the roll thereon and arranged to support the roll at the rear of the heel end of the shoe, a device for locking said receiver against further depression to hold it in supporting position, and a spring arranged to act on said arm to position the receiver relatively close to the heel end of the shoe, the machine being

constructed to stop said arm at a predetermined point in the movement of the jack and to hold it against the resistance of said spring with the receiver in roll-supporting position while the jack continues its movement to carry the shoe beyond the roll.

30. In a leveling machine, a shoe support and a leveling tool relatively movable lengthwise of a shoe on said support to cause the tool to operate progressively along the bottom of the shoe and to pass beyond an end of the shoe, a device arranged to support the tool against movement in the direction of the leveling pressure when the tool is beyond the end of the shoe, said device being mounted for movement lengthwise of the shoe toward or from the end of the shoe, and manually operated means for controlling such movement of the device.

31. In a leveling machine, a shoe support and a leveling roll relatively movable lengthwise of a shoe on said support to cause the roll to operate progressively along the bottom of the shoe and to pass to the rear of the heel end of the shoe, a roll receiver for supporting the roll at the rear of the heel end of the shoe, said roll receiver being mounted for movement lengthwise of the shoe toward or from the heel end, and manual means for moving said receiver away from the shoe to facilitate the removal of the shoe from the support and the mounting of another shoe thereon.

32. In a leveling machine, a leveling roll and a jack relatively movable to cause the roll to traverse the heel end of a shoe on the jack and to pass to the rear of the heel end, a roll receiver on the jack for supporting the roll at the rear of the heel end of the shoe, said roll receiver being mounted for movement lengthwise of the shoe toward or from the heel end, and manual means for jacking the shoe arranged also to control said movement of the roll receiver.

33. In a leveling machine, a leveling roll, a jack movable to cause the roll to traverse the heel end of a shoe thereon and to pass to the rear of the heel end, a roll receiver carried by the jack for supporting the roll at the rear of the heel end of the shoe, said roll receiver being mounted for movement lengthwise of the shoe toward or from the heel end, a spring tending to move said receiver toward the heel end of the shoe, a hand lever for jacking the shoe, and means controlled by said hand lever for moving said receiver away from the heel end of the shoe or for releasing it to permit it to be moved toward the shoe by its spring.

34. In a leveling machine, a shoe support, a plurality of leveling rolls arranged to be positioned one in advance of another lengthwise of a shoe on said support, the shoe support and the rolls being relatively movable lengthwise of the shoe to cause one of the

rolls to traverse the heel end of the shoe and to pass to the rear of the heel end, a device arranged to support said last-named roll against movement in the direction of

- 5 the leveling pressure at the rear of the heel end of the shoe, said device being movable heightwise of the shoe to a position determined by the shoe, and automatic means for locking said supporting device against 10 any substantial movement in the direction of the leveling pressure from the position thus determined.

35. In a leveling machine, a shoe support, a plurality of leveling rolls arranged to be positioned one in advance of another lengthwise of a shoe on said support, the shoe support and the rolls being relatively movable lengthwise of the shoe to cause one of the rolls to traverse the heel end of the shoe and to pass to the rear of the heel end, a roll receiver arranged to support said last-named roll against movement in the direction of the leveling pressure at the rear of the heel end of the shoe, said receiver being compressible automatically to a position determined by engagement of said roll with the bottom of the shoe, and automatic means controlled by the relative movement of the shoe support and the rolls for locking the receiver against any substantial further depression from the position thus determined.

36. In a leveling machine, a shoe support, a plurality of leveling tools arranged to be positioned one in advance of another lengthwise of a shoe on said support, said shoe support and tools being relatively movable lengthwise of the shoe to cause the tools to operate progressively along the bottom of the shoe, and automatic means for controlling each of said tools independently with respect to movement heightwise of the shoe to determine the time of its engagement with the shoe.

37. In a leveling machine, a shoe support, a plurality of leveling rolls arranged to be positioned one in advance of another lengthwise of a shoe on said support, said shoe support and rolls being relatively movable lengthwise of the shoe to cause the rolls to operate progressively along the bottom of the shoe, and automatic means comprising separate cams for controlling the different respective rolls independently with respect to movement heightwise of the shoe to determine the time of their engagement with the shoe.

38. In a leveling machine, a shoe support, a plurality of leveling rolls arranged to be positioned one in advance of another lengthwise of a shoe on said support, said shoe support and rolls being relatively movable lengthwise of the shoe to cause the rolls to operate progressively along the bottom of the shoe, roll carriers for the different respective rolls movable independently of

each other heightwise of the shoe, and a separate power-operated cam associated with each roll carrier for controlling such heightwise movement.

39. In a leveling machine, a shoe support, a plurality of leveling rolls arranged to be positioned one in advance of another lengthwise of a shoe on said support, said shoe support and rolls being relatively movable lengthwise of the shoe to cause the rolls to operate progressively along the bottom of the shoe, the rolls being movable independently of each other heightwise of the shoe, and separate controlling devices each comprising a cam and a spring operated by said cam for pressing the different respective rolls upon the bottom of the shoe.

40. In a leveling machine, a shoe support, a plurality of leveling rolls arranged to be positioned one in advance of another lengthwise of a shoe on said support, said shoe support and rolls being relatively movable lengthwise of the shoe to cause the rolls to operate progressively along the bottom of the shoe, the rolls being movable independently of each other heightwise of the shoe, and automatic for controlling such heightwise movement of the different respective rolls independently to cause them to come successively into engagement with the shoe.

41. In a leveling machine, a shoe support, different leveling rolls arranged to be positioned one in advance of the other lengthwise of a shoe on said support, said shoe support and rolls being relatively movable lengthwise of the shoe in an automatically determined cycle to cause the rolls to operate progressively along the bottom of the shoe, and automatic means for moving one of the rolls heightwise of the shoe into and out of engagement with the shoe at different times in the cycle from the other roll.

42. In a leveling machine, a shoe support, different leveling rolls for operating respectively upon the heel end portion of the shoe and upon other portions of the shoe, said shoe support and rolls being relatively movable lengthwise of the shoe to cause the rolls to operate progressively along the bottom of the shoe, and means for moving the heel end roll heightwise of the shoe independently of the other roll to limit it substantially to engagement with the heel end of the shoe.

43. In a leveling machine, a shoe support, different leveling rolls for operating respectively upon the heel end of the shoe and upon the forepart and shank portions of the shoe, said shoe support and rolls being relatively movable lengthwise of the shoe to cause the rolls to operate progressively along the bottom of the shoe, the rolls being so arranged that both are positioned at times over the forepart of the shoe in the relative movement of the rolls and the shoe support,

and means for controlling the heel end roll to prevent it from engaging the shoe when it is over the forepart of the shoe.

44. In a leveling machine, a shoe support, 5 different leveling rolls arranged to be positioned one in advance of the other lengthwise of a shoe on said support, said shoe support and rolls being relatively movable lengthwise of the shoe to cause the rolls to 10 operate progressively along the bottom of the shoe, the rolls being so arranged that each is positioned at times over the ball of the shoe in the relative movement of the rolls and the shoe support, and means for 15 controlling movement of one of the rolls heightwise of the shoe independently of the other roll to prevent its engagement with the ball of the shoe.

45. In a leveling machine, a shoe support, 20 a leveling roll for operating upon the heel end portion of a shoe on said support, the

shoe support and the roll being relatively movable in such relation that the roll is positioned at times over other portions of the shoe than the heel end, and automatic means 25 for controlling movement of said roll heightwise of the shoe to limit it substantially to engagement with the heel end of the shoe.

46. In a leveling machine, a shoe support, 30 a leveling roll for operating upon the heel end portion of a shoe on said support, the shoe support and the roll being relatively movable in such relation as to cause the roll to be positioned at times over the ball of the shoe, and mechanism automatically operative 35 in the relative movement of the roll and support to lift the roll clear of the ball of the shoe when it is positioned thereover.

In testimony whereof I have signed my name to this specification.

ERASTUS E. WINKLEY.
